UNITED STATES PATENT OFFICE.

AYE HARRIS, OF CINCINNATI, OHIO.

MOP.

Application filed November 5, 1921. Serial No. 513,201.

To all whom it may concern:

Be it known that I, AYE HARRIS, a citizen of the United States, residing at the city of Cincinnati, in the county of Hamilton and 5 State of Ohio, have invented certain new and useful Improvements in Mops, of which the following is a specification.

The object of my invention is to provide a cheap, simple and highly efficient mop device, in which the handle and the mop part are united in a unique manner.

By using my invention, I am enabled to assemble the parts which form the mop quickly and satisfactorily, and if the handle 15 of the mop becomes broken, I can replace it readily, and if the strands which form the mop become worn and need replacement, I can place a new mop upon the handle, in either case overcoming the necessity of pur- 20 chasing a new mop.

In my new mop, the handle and mop part are united together in a manner to form a tight joint, which will be of a permanent nature and not become shaky or wobble, but 25 retain a uniform and serviceable condition.

Its features and advantages will readily become apparent from the following specifications.

In the accompanying drawing forming a 30 part of this specification:

Fig. 1, is an assembled view of the mop, the handle being partly broken away,

Fig. 2, is a section on line 2—2 of Fig. 1,

Fig. 3, is a section on line 3—3 of Fig. 1,

35 Fig. 4, is a view of the inner housing or ferrule,

Fig. 5, is a section of the outer housing or ferrule, and

Fig. 6, is a view of the mop spreading 40 ring and holder.

In the drawing the mop handle is marked 1, and may be of any kind; the mop part being marked 2 and may also be of any form and kind.

45 In carrying out my invention, I provide a ferrule or housing 4 having a knurled surface 5 on a flange part 11 and carrying a screw thread 12 and provided with a hole 5'; this represents the inner ferrule or hous- 50 ing. I also provide an outer ferrule or hous- ing 6, having a contracted mouth 9 and rounded off top edge 8; at the bottom this ferrule carries a flange 7 and said ferrule is internally screw threaded, see screw 55 threads 10. The outer ferrule 6 carries a

knurled part 13. I provide a retaining ring 3 to hold and distribute the threads or strands which make up the mop part 2. These parts are united together in the following manner: The inner ferrule 4 is first 60 slipped down over the mop handle until it reaches its proper position, at the bottom thereof and a screw is placed through the hole 5' to retain the said ferrule on the mop handle; the mop strands 2 are then slipped 65 through the ring 3 until the middle of said strands is reached; they are then worked around said ring 3 until they hang over the same and form an annular uniform mop part; the ring with the mop strands or part 70 2 is then placed over the handle until the ring carrying the mop part goes down as far as it will resting upon the ledge or flange 11 and on the inner ferrule; the outer fer- rule 6 is then run over the mop handle and 75 screwed down upon the ring and mop strands, screwing down over the screw threads 12, by reason of the screw threads, 10, screwing thereon until the flange or ledge 11 is tightly engaging against the mops 80 strands 2 and ring 3, as shown in Fig. 2.

It will be seen by this operation that the mop parts are thus complete to form a mop. When the handle is broken, or the mop is 85 worn out, the ferrule 6 can be unscrewed from the ferrule 4, and a new handle or new mop part placed in position, the same as before described.

It will be observed that this will make a first class and standard mopping device, and 90 the size of the mop part 2, can be regulated by the number of strands used in making the mop part.

The outer ferrule 6 is contracted at the upper part 9, so that a more firm hold is 95 secured on the mop handle, and by this means it is also kept more tightly in place, and prevented from wobbling and coming loose; this ferrule 6 is also rounded off at 8 in order to get a better hand hold. It 100 will also be observed that the ferrule 4 is cut away at 14, at its top, so that the flange 15 on the ferrule 6, at its top part can rest upon said cut away part 14, to make a tight, close and serviceable joint between all said 105 parts. By the term ferrule or housing, a form of sleeve is meant.

While I have described one specific manner in placing my invention into practical form, it will be readily observed that I can 110

change the same to some extent, and I wish to be understood as not limiting myself to the exact construction shown.

What I claim as new and my invention 5 and desire to secure by Letters Patent is:

In a mop of the character described, a handle, a mop part, a sleeve secured to the handle, a ring holding mop strands support-

ed on said sleeve, a second ferrule capable of being screwed down onto the said first 10 mentioned sleeve, clamping the ring holding the mop part tightly in position.

In testimony whereof, I affix my signature at Cincinnati, Ohio, this 31st day of October, 1921.

AYE HARRIS.
